UNITED STATES PATENT OFFICE.

ORVILLE P. MOON AND HERMAN L. MARBACH, OF LORAIN, OHIO.

HYDROCARBON-BURNER.

SPECIFICATION forming part of Letters Patent No. 608,785, dated August 9, 1898.

Application filed August 16, 1897. Serial No. 648,340. (No model.)

To all whom it may concern:

Be it known that we, ORVILLE P. MOON and HERMAN L. MARBACH, citizens of the United States, residing at Lorain, in the county of Lorain and State of Ohio, have invented certain new and useful Improvements in Hydrocarbon-Burners; and we do declare that the following is a full, clear, and exact description of the invention, which will enable others skilled in the art to which it appertains to make and use the same.

Our invention has reference to hydrocarbon-burners of the variety in which wicks are employed to burn kerosene-oil.

In the accompanying drawings, Figure 1 is an elevation, partly in section, of the combustion or mixing tubes and the wick-tubes and the drums therefor and the means for automatically raising the upper tubes and their drum, substantially as hereinafter described, the upper tubes and drum in this view being in working position. Fig. 2 is a plan view of the mechanism shown in Fig. 1, looking down on a line taken across the lower drum and the wick-tubes and omitting or cutting off the upper drum and combustion or burner tubes, the casing B being omitted in this view to avoid confusion of lines. Fig. 3 is a central sectional elevation of the mechanism, tubes, and drums shown in Fig. 1 and taken on a line corresponding substantially to 3 3, Fig. 2. Fig. 4 is a perspective elevation of the front plate and the means outside said plate for manipulating the wick and for releasing the mechanism which lifts the mixing-tubes, as hereinafter described. Fig. 5 is a plan view of the combustion or mixing tubes alone. Fig. 6 is a vertical sectional elevation on line 6 6, Fig. 5, showing the manner of uniting the combustion-tubes and the vanes thereon, which also support the surrounding drum. Fig. 7 is a sectional elevation of the handle of the wick-spindle and showing a section of the wick-spindle and associated parts, as hereinafter described.

The main object of the invention shown in the several views is to raise the combustion or mixing tubes or chamber and the drum about the same when the wick is turned down and the burner extinguished. We are of course aware that mechanism having this object in view in any broad sense is not original

in this application; but we are not aware that any one has ever before devised, made, or used devices accomplishing the lifting of the mixing-chamber by mechanism of the character and having the operation substantially as herein shown and described.

In this mechanism there is no mechanical connection whatever between the wick-operating spindle and the tube-lifting mechanism, and yet said parts are so related or associated and arranged for the convenience of operation that in grasping the wick-controlling handle to turn the wick down the operator naturally and automatically releases the tube-lifting mechanism, so that the counterweight provided for that purpose may lift the mixing tubes or chamber out of contact with the wick-tubes, and thus not only break mechanical connection and avoid the creeping of the oil, but afford opportunity for lighting the wick when again turned up before the said tubes or chamber are restored to their operative position.

It will also be observed as a peculiarity of this mechanism that all the operative parts for controlling the mixing chamber or tubes are on the outside of the wick-tubes and in position where they may be easily reached and their relations and operation observed without removing any of said tubes. Other features of novelty are the means for uniting the mixing-tubes and supporting their drum and for changing the relations of the wick-spindle handle, all as hereinafter more fully described.

Referring now to the drawings for a detailed consideration of the parts, A represents the usual wick chamber or tubes, and B is the usual drum about the same. C represents the inner perforated combustion or mixing tube, and D the outer mixing-tube, said tubes together constituting what we term the "combustion" or "mixing" chamber, and E is the drum which surrounds and incloses these two tubes and constitutes a continuation of the lower drum B, as is now common in this art.

In the use of burners of this kind it is of first importance that the combustion-chamber should be uniform in width all around, so that there will be even combustion and an even flame at the top of the burner. It is very desirable also that the connection be-

tween the tubes C and D be such that the burner will stand shipping and a large amount of rough handling without disturbing the uniform relations thereof. To these several 5 ends we insert vertical vanes or partitions 2 between said tubes, which project laterally therefrom at four different points in this instance to afford the necessary support for the outer drum E. It will be noticed that the 10 outer tube D is made in four vertical sections having outwardly-extending flanges 3, between which the vanes 2 are riveted, while the inner tube C is firmly riveted upon the edge of said vanes. This makes a firm and solid 15 structure of the two tubes and their vanes, and said parts are always movable together. Of course in some respects our invention would operate as well to have these tubes disconnected and so that the outer tube might be 20 raised separately, but we prefer the present construction.

We also have found it advantageous for a 25 number of reasons to have the outer drum E easily removable from the combustion-chamber and for this reason have so constructed the said drum and the vanes 2 that while said vanes form a support for the drum the drum can be easily lifted off or separately raised. To form such support, we have in this instance 30 simply produced a bead 4 around the inside of the top of the drum, which rests on shoulders on the said vanes; but any other suitable means of support having the same function may be adopted. Now in order that said 35 tubes C and D and drum E may be raised and lowered together, as hereinbefore described, and to prevent the creeping of oil and for convenience of lighting the wick we employ two rods or equivalent parts F, rigidly fixed 40 to the said tubes C and D or the vanes connecting them and working in suitable guides 5 on opposite sides of the wick-chamber and on the outside thereof. These rods, one or both, project below the wick-chamber some 45 distance, and the lifting mechanism operates in connection with one of these rods, as shown in Fig. 1. Here it will be seen that we employ a counterbalanced rod G, pivoted in a suitable support 6 and carrying a counter- 50 weight H at its rear and a circular head J at its front end. At its middle the said rod has a substantially U-shaped downward bend 8, flattened at its middle in this instance, where it bears against the end of rod F; but 55 this flattening may be omitted or a flat piece or the like may be substituted therefor. The wheel-shaped head J is loose or free to turn on its spindle. The counterbalance-rod G, carrying this wheel, projects at its front end 60 through the front plate K, parallel with the wick-spindle, and the said plate has a vertical slot 9, with a hook or notch 10 at its edge to engage the rod G and hold the counterweight in raised position. When this occurs 65 and the counterweight is up, as seen in Fig. 1, the combustion-chamber and its drum are down in working position, and when the said

rod G is released from the hook 10 the counterweight at once exerts itself and by its own weight or gravity bears against the vertical 70 rods F and raises said tubes C D and drum E and throws the said rod and parts into the position seen in dotted lines, Fig. 1.

The wick is controlled by means of the spindle L, wick-raiser M, and hand-wheel N, the 75 said raiser M having a toothed projection 10', engaged by pinion 11 on the spindle L and operating in a well 12 provided for that purpose. The hand-wheel N controls the wick and is designed to be rotatable within certain limits, according as it is desired to raise the wick higher or lower. For this purpose the said wheel is provided with a hub having an arm 13 arranged to engage a stop projection 14 on the plate K, so that when 80 the wheel N is turned to its limit it will be stopped by the parts 13 and 14. However, it is desirable to vary these relations, so as to feed more or less wick, as already indicated, and to this end the wheel N is rotarily 85 adjustable on its spindle 15 and is held in any adjusted relation on said spindle by the flutes or serrations 16 on the rod L, which are engaged by corresponding flutes or serrations on the socket 17 in said handle. 90 When the parts are in working position, the said socket engages over the serrated extremity 16 and is locked thereon, being held in that position by the spiral spring 18, confined within the hub of the handle from its 95 outside by a nut 19. Hence when the relation of projections 13 and 14 is to be changed to raise the wick higher the handle is simply thrown back against spring 18 and rotated so as to bring the projection 13 farther 100 back, and then the spring is permitted to exercise its tension and carry the handle again into working position, where it will remain until further adjustment is made. As the wick is consumed this adjustment of course 105 is employed to give more wick, and the handle N may be moved one or more notches or serrations forward or back, as the case may require.

When the wick-spindle L is turned to lower 110 the wick and extinguish the burner, it is turned toward the wheel J in the direction of the arrow shown in Fig. 4, and the space between the two wheels or heads J and N is designed to be so slight, comparatively, that 115 the fingers cannot engage wheel N and turn the wick down without such contact with wheel J as will release the counterweighted rod G from its engagement in the hook or notch 10. Hence it follows when the wick is 120 turned down and the burner extinguished that the counterweight mechanism is automatically thrown into action without any special effort or manipulation on the part of the operator and without exercising any 125 care or forethought to effect this result, and yet if for any reason it be desired that the combustion-tubes be not raised when the wick is turned down the hand-wheel N can 130

be turned purposely to avoid such result, the connection between wheels J and N being incidental and not mechanical. When it is desired to keep on turning the wick in either 5 direction, up or down, the pivoted part P, which carries stop projection 14, need simply be raised, and then the wick-spindle can be turned without limit.

What we claim as new is—

- 10 1. The combination of an annular wick-tube, a mixing-chamber situated thereabove, one of the walls of said mixing-chamber being adapted to be raised and lowered, and means situated outside said wick-tube and adapted to lift the movable wall, said means comprising a wick-spindle, and a counterbalanced rod for lifting the mixing-chamber having their extremities separate but in proximity to each other, whereby when the operator turns the wick-spindle his hand normally bridges the intervening space and releases said counterbalanced rod, substantially as described.
- 15 2. The combination of the wick-tubes, and the operating mechanism for the wick, a mixing-chamber situated thereabove having one of its walls adapted to be raised and lowered, and means to lift the said movable wall comprising a counterbalanced member mechanically 20 independent of the wick-operating mechanism and constructed to be separately operated, and handles for operating said separate lines of mechanism located side by side, whereby when desired one hand normally 25 actuates both handles, substantially as described.
- 30 3. The wick-tubes and the wick-spindle and its handle, in combination with the mixing-tubes, a counterbalanced mechanism to raise 35 said mixing-tubes, and a device for releasing said counterbalanced mechanism located in proximity to said wick-spindle handle but mechanically independent thereof, whereby when the wick-spindle is rotated the said 40 counterbalanced mechanism is normally released by the same hand that operates said spindle, substantially as described.
- 45 4. The wick-tubes and the mixing-tubes,

lifting-rods for the mixing-tubes fixed on the outside thereof, and guides for said rods on the outside of the wick-tubes, in combination with a counterbalanced rod engaging one of said lifting-rods, a wick-raising spindle substantially parallel to said counterbalanced rod, and hand-engaging portions on said spindle and rod in such relation that when the operator rotates said spindle his hand normally releases said counterbalanced mechanism for the wick-tubes, substantially as described.

5. The wick-tubes and the spindle and handle therefor, in combination with the mixing-tubes and lifting mechanism for said tubes having a counterbalanced rod, and a head on said rod in close proximity to the handle of the wick-spindle, whereby the same hand which operates the wick-spindle normally releases the mechanism for raising the combustion-tubes, substantially as described.

6. The wick-tubes and the mixing-tubes, the spindle and its handle to operate the wick, and a counterweighted rod to raise the mixing-tubes; a catch to engage and hold down said counterbalanced rod and a handle on the extremity of said rod in proximity to the handle on the wick-spindle whereby the same hand of the operator at the same time contacts with and operates both said handles, substantially as described.

7. The outer and the inner mixing-tubes, the said outer tubes having outwardly-extending vertical flanges and vanes fixed to said flanges and connecting said tubes, substantially as described.

8. The two mixing-tubes and the vertical vanes projecting laterally therefrom at intervals, in combination with the drum removably supported on said vanes, substantially as described.

Witness our hands to the foregoing specification this 20th day of July, 1897.
